J. J. WEBB.
SHOE BLACKING STAND.
APPLICATION FILED NOV. 26, 1919.
1,357,666. Patented Nov. 2, 1920.

UNITED STATES PATENT OFFICE.

JAMES JULIOUS WEBB, OF BOLEY, OKLAHOMA.

SHOE-BLACKING STAND.

1,357,666.

Specification of Letters Patent.

Patented Nov. 2, 1920.

Application filed November 26, 1919. Serial No. 340,820.

To all whom it may concern:

Be it known that I, JAMES JULIOUS WEBB, a citizen of the United States, residing at Boley, in the county of Okfuskee and State 5 of Oklahoma, have invented certain new and useful Improvements in Shoe-Blackening Stands, of which the following is a specification, reference being had to the accompanying drawings.

10 This invention relates to certain improvements in shoe blacking stands, and it is an object of the invention to provide a device of this general character having novel and improved means whereby a shoe may be effectively held in a position to facilitate the 15 polishing thereof.

Another object of the invention is to provide a novel and improved device of this general character embodying a structure 20 whereby a shoe to be polished may be supported in a position to relieve the operator of inconvenience of stooping or bending.

A further object of the invention is to provide a device of this general character 25 provided with novel and improved means for engaging the heel and sole portions of a shoe to anchor the same in a working position upon the stand.

The invention consists in the details of 30 construction and in the combination and arrangement of the several parts of my improved shoe blacking stand whereby certain important advantages are attained and the device rendered simpler, less expensive and 35 otherwise more convenient and advantageous for use, as will be hereinafter more fully set forth.

The novel features of my invention will 40 hereinafter be definitely claimed.

45 In order that my invention may be the better understood, I will now proceed to describe the same with reference to the accompanying drawings, wherein:

Figure 1 is a side elevation of a stand 45 constructed in accordance with an embodiment of my invention, a shoe being applied thereto, and a last within the shoe.

Fig. 2 is an enlarged fragmentary view 50 in cross section taken through the heel portion of the stand;

Fig. 3 is an enlarged cross sectional view taken through the forward portion of the stand;

Fig. 4 is a cross sectional view illustrating a slightly modified form of the invention.

As disclosed in the accompanying drawings, S denotes a standard of a desired length, and which has secured to one end portion thereof a base plate P, which affords 60 means whereby the standard S may be maintained vertically disposed, and which is also provided with openings 1, whereby the device in its entirety may be secured through the instrumentality of screws or the like in 65 a desired location.

B denotes an elongated head or base secured at substantially its central portion to the upper extremity of the standard S, said bed or base B being approximately in per- 70 pendicular relation to the standard S.

Secured to the side faces or edges of the bed or base B adjacent an end thereof are the upstanding fastening members F adapted to coact with the heel of a shoe. Each of 75 the members F has its opposite end portions offset, with the lower offset portion 2, inwardly disposed with respect to the bed or base B, and said lower offset portion 2 secured to the bed or base B by screws 3 or 80 the like.

Disposed around the upper or free end portions of the members F is a continuous band 4, preferably substantially square in top plan. The band 4 defines a central open- 85 ing of dimensions to receive shoe heels of different sizes.

Threaded through the band 4 and in swivel connection, as at 5, with the upper portion of one of the members F is a 90 threaded shank 6, provided at its outer end portion with a head 7 or the like, whereby said shank may be conveniently rotated manually. The members F possess a certain degree of inherent resiliency, and after the 95 heel of a shoe has been disposed within or through the opening defined by the band 4, the members F are caused to have clamping action thereon upon requisite rotation of the threaded shank 6. By this means the heel 100 portion of the shoe to be polished is effectively maintained above the bed or base B while the band 4 surrounding the heel operates to hold the shoe against undue movement longitudinally of the bed or base B. 105

Carried by the opposite end portion of the bed or base B are the longitudinally spaced pairs of fastening members M, with the members of each pair in transverse alignment, and secured to the side faces or edges 110 of the bed or base B. Each of the members M comprises a vertical portion 8, having its

opposite end portions offset with the lower offset portion inwardly disposed, and secured by the screws 9 or the like to the side faces of the bed or base B. The upper or outer extremity of the upper offset portion of the member M is continued by an outwardly directed extension 10, substantially perpendicular to the vertical portion 8, and said extension 10 terminates in an upstanding lip or flange 11.

Threaded through the portion 8 of one of the members M of each pair is a threaded shank 12, having one end portion swiveled, as at 14, with the vertical portion 8 of the second member of the pair. The opposite end portion of the shank 14 is provided with a head 15 or the like, whereby said shank may be readily rotated in accordance with the requirements of practice.

The ball and toe portions of a shoe rest upon the extensions 10 of the members M, and upon requisite rotation of the shanks 12 the lips or flanges 11 have clamping action upon the sole of the shoe, and thereby hold or maintain the shoe in working position above the bed or base B. The action of the lips or flanges 11 is accomplished by the inherent resiliency possessed by the members M.

In the form of invention illustrated in Fig. 4 the lower portion of each of the members M' is provided in its inner face with a transversely disposed groove 16, preferably dove-tail, and which snugly engages upon an outstanding flange extending along the side face of the bed or base B adjacent the top thereof. By this means it will at once be understood that the member M' may be readily adjusted longitudinally of the bed or base B, as may be required by the size of the shoe to be polished.

To facilitate the polishing of a shoe it is of advantage to insert a last within the shoe to maintain the same in substantially the same condition as when applied to the foot of a person.

From the foregoing description it is thought to be obvious that a shoe blacking stand constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

1. A stand of the class described comprising a base, a plurality of pairs of clamping members carried thereby, the members of each pair being in alinement, and means coacting with the clamping members of each pair for moving the same one toward the other, said means including a band surrounding a pair of said fastening members, said band defining a central opening adapted to receive the heel of a shoe.

2. A stand of the class described comprising a base, heel clamping members carried thereby, a band surrounding said members and defining an opening to receive the heel of a shoe, and an operating member adjustably engaging the band and bearing upon one of the fastening members whereby said fastening members are moved one with respect to the other.

3. A stand of the class described comprising a base, heel clamping members carried thereby, a band surrounding said members and defining an opening to receive the heel of a shoe, and a shank threaded through the band and in swivel connection with one of the clamping members.

In testimony whereof I hereunto affix my signature.

JAMES J. WEBB.
